UNITED STATES PATENT OFFICE.

JOHN COX, OF HOT SPRINGS, ARKANSAS, ASSIGNOR OF TWO-FIFTHS TO WILLIAM P. PARKS, OF HOT SPRINGS, ARKANSAS.

SPRING-WHEEL FOR VEHICLES.

1,200,316.

Specification of Letters Patent.

Patented Oct. 3, 1916.

Application filed April 20, 1916. Serial No. 92,428.

To all whom it may concern:

Be it known that I, JOHN COX, a citizen of the United States, residing at Hot Springs, in the county of Garland and State 5 of Arkansas, have invented certain new and useful Improvements in Spring-Wheels for Vehicles; and I do declare the following to be a full, clear, and exact description of the invention, such as will enable others skilled 10 in the art to which it appertains to make and use the same.

This invention relates generally to vehicle wheels, and more particularly to that class of wheels which are elastic or yieldable between the hub and tire. 15

The primary object of the invention is to provide a wheel of this character having an improved form of spoke which is so constructed and arranged as to provide a maximum 20 amount of resiliency, and to this end it consists of a series of spokes of approximately sinuous form arranged between the hub and rim.

Another object of the invention is to provide 25 a wheel having resilient spokes of this character having an improved manner for attaching the inner ends of the spokes to the hub.

A further object of the invention is to 30 provide an improved form of rim for a wheel of this character.

An additional object resides in the provision 35 of a device which will be simple, strong, durable and inexpensive in construction, efficient and reliable in operation, and well adapted to the purpose for which it is designed.

With these and other objects in view, the invention consists of certain novel features 40 of construction, and the combination and arrangement of parts as will be herein-after fully described and claimed.

In the accompanying drawings in which similar reference characters designate like 45 parts throughout the several views: Figure 1 is a front elevation of a resilient wheel constructed in accordance with this invention; Fig. 2 is a side elevation of the same; Fig. 3 is a vertical sectional view taken on 50 the plane of the line 3—3 of Fig. 1; and Figs. 4 and 5 are vertical sectional views through one of the spokes, showing particularly the means of connection of the same to the rim sections and hub respectively.

Referring more particularly to the drawings, the numeral 1 designates the body portion of the hub of a wheel constructed in accordance with this invention. This body portion 1 is preferably made of wood and is provided with a centrally arranged bore 60 2 having a metallic lining 3 therein, one of the ends of the lining 3 being provided with ears 4 adapted to be engaged by suitable fastening elements to retain said lining in place. Arranged on the outer sides of the 65 body portion 1 in any suitable manner is a cylindrical metallic casing 5, the ends of which are provided with attaching elements to be engaged by the inner ends of the spokes of the wheel. These attaching elements are here shown in the form of circumferentially spaced lugs 6 which are struck inwardly from the ends of the casing 5 and having slots 7 arranged in their bent portions as shown. Extending from 70 the hub of the wheel is a double series of spokes comprising substantially a plurality of spaced pairs of sinuous or zig-zag resilient strips 8. The inner ends of these strips 8 are reduced in width to form 80 tongues 9 which are extended through the aforesaid slots 7 and then bent inwardly upon the lugs 6, thereby firmly securing said strips to the attaching elements. The outer ends of the strips 8 are integrally connected by transverse bars or straps 10, and secured to these straps 10 is a pair of spaced 85 rim sections or rings 11. These rim sections 11 are here shown as being clamped and secured between the inner sides of the straps 90 10 and the outer folds of the strips 8. The rim is adapted to receive a solid rubber or other suitable tire (not shown).

Disposed between the spokes or strips 8 are diagonally crossed braces 12, the ends 95 of which are connected to the upper and lower inner folds of the strips in any convenient manner. This it will be readily understood prevents the spokes of the rim from shifting longitudinally with respect 100 to the hub, but allows a free yielding movement of the arm.

From the foregoing description, taken in connection with the accompanying drawings, the operation and construction of the 105 invention will be readily understood without a more extended explanation.

As various changes in form, proportion

and the minor details of construction may be resorted to without departing from the spirit of the invention, I do not wish to be limited to the construction herein shown and described other than that set forth in the appended claims.

I claim:

1. A wheel of the class described comprising a cylindrical hub, a cylindrical casing surrounding said hub, circumferentially spaced lugs struck inwardly from the ends of said casing and having slots arranged in their bent portions, a rim, and a plurality of resilient strips disposed between said hub and said rim and having their outer ends connected with the latter, the inner ends of said strips being reduced in width to form tongues, said tongues being ex-
- 10
- 15

tended through the slots in said lugs and then bent inwardly upon the same.

2. A wheel of the class described comprising a hub, a double series of sinuous resilient strips extending radially from the ends of said hub, transverse straps disposed between the outer ends of said strips and integrally connected with the same, and a pair of spaced rings clamped and secured between the inner sides of said straps and the outer folds of said strips.

In testimony whereof I have hereunto set my hand in presence of two subscribing witnesses.

JOHN COX.

Witnesses:

JAMES W. WALKER,
DAVID T. YOUNG.
